UNITED STATES PATENT OFFICE.

ROBERT P. KING, OF GREENSBORO, NORTH CAROLINA.

PORTABLE WALL CABINET.

Application filed April 14, 1925. Serial No. 23,000.

This invention relates to portable wall cabinets.

The object is to provide a wall cabinet, such as are commonly used in the bathrooms 5 of houses for holding medicines, toilet articles and the like, said cabinet being placed in any desired location and equipped with proper electrical connections, and having the fixed portions of such connections so arranged at the back of the cabinet as to permit the cabinet to be hung or suspended flat against the wall without interference by the same.

Another object is to provide a device of 15 this character which is equipped with suitable side lights carried by the cabinet to illuminate each side of the face or head of the user while facing a mirror mounted in the cabinet door which, when shut, forms a 20 closure for the cabinet and affords a convenient location for the mirror, which is especially useful in bathrooms not otherwise equipped.

A final object is to provide a second mirror 25 mounted on the top of the cabinet and swingable and extensible into a position for coaction with the first-named mirror to enable the user to see reflected in one or the other, the back of the head, or other portions 30 thereof, while in the act of completing the toilet or during the process of shaving, etc.

A full and complete understanding of the invention may be obtained from a consideration of the following detailed description, 35 taken in connection with the accompanying drawings forming a part of this specification, it being understood that while the drawings show a practical form of the invention, the latter is not to be confined to 40 strict conformity with the showing thereof, but may be changed or modified, so long as such changes or modifications mark no material departure from the salient features of the invention, as specifically pointed out in 45 the appended claims.

In the drawings, in which similar reference characters designate corresponding parts throughout the several figures:—

Figure 1 is a front elevation of the improved wall cabinet;

Figure 2 is a rear elevation thereof;

Figure 3 is a side view showing the supplemental mirror in use;

Figure 4 is a top plan view of the same.

Referring to the drawings there is shown 55 a cabinet of ordinary construction and de-

sign and having the usual dimensions, the same being somewhat higher than wide, as viewed from the front, and having a depth to hold bottles or other articles on the customary shelves (not shown) located therein. 60

The top 1 of the cabinet is provided with eyes 2 near the rear edge thereof for suspending the same from nails or screws on the wall at any desired location, and the front of 65 the cabinet is in the form of a door 3 hinged in the usual manner and provided on its front face with the ordinary mirror 4.

Side wings 5 are secured to the back of the cabinet by screws 6 or otherwise, and the 70 rear faces of the wings are adapted to lie flat against the wall, the said wings being formed, preferably, in some artistic design and adapted to be finished on their front faces in a manner to correspond with the cab- 75 inet proper.

The rear faces of the wings are provided with inclined grooves 7 extending part way through the same and terminating at their lower ends in circular enlargements 8 located substantially at the vertical center lines of the exposed front faces thereof, the said inclined portions extending to the inner edges of the wings where attached to the back of the cabinet. Any standard outlet 80 box 9 may be employed to be fastened in the said enlargements 8, and the same have means for connection with relatively short lengths of protective material 10, such as 85 tubing or the flexible protector known as "B. X." of the flat type in which there is located the usual electrical conductor or wire. 90

The rear faces of the boxes 9 and the connected protectors lie substantially flush with 95 the rear faces of the wings so that they do not prevent the latter from contacting with the supporting wall throughout their surfaces, and the upper ends of the protectors, owing to the inclination of the slots confining the same, converge towards each other at the top of the cabinet, where the same are connected to another outlet box 11 secured to the rear edge of the top 1 of the cabinet and preferably countersunk into the same, as 100 indicated at 12, the said top extending rearwardly beyond the rear face of the back of the cabinet, so that said box 11 does not interfere with said contact. 105

The box 11 is provided with an inlet for 110 an extension cord 13, having the usual attachment plug 14 suitably connected to its

free end, so that the cabinet may be hung in any convenient position in the bathroom or other room, and suitable connection made with the source of electrical energy for the 5 lighting of the cabinet.

Suitable lamp brackets 15 are secured in position on the front face of the side wings 5, and connection is made to the outlet boxes 9 on the rear thereof, said brackets being 10 preferably of some ornamental design and adapted to receive electric lamps 16 in the usual manner, and having pull chains or turn buttons for controlling the lights. The B. X. or tubing serves to strengthen the back 15 of the cabinet and to more securely tie the side wings thereto and, as has been stated, the manner of mounting the same in the grooves permits the entire cabinet to abut against the wall in a manner to avoid rock- 20 ing movement of the same.

Mounted on the top 1 of the cabinet and adjacent to the rear edge thereof is a socket 17, in which there is seated the enlarged lower end of an arm 18, the major portion 25 of which is bent downwardly at an angle, as shown at 19, and is in the form of tubing, the length and angularity being such as to permit said arm to be swung to either side to escape the upper corners of the cabinet 30 and to lie adjacent to the wall when not in use.

An extensible rod 20 is seated for sliding movement in said angular extension of the tubular arm and said rod is bent downwardly at its outer, free end and mounted in a swivel 21 having depending ears 22, in which are engaged eyes 23 connected to a mirror frame 24 having a mirror 25 on one or both faces thereof.

40 The frictional engagement of the rod 20 in the tubular extension 19 is sufficient to support the weight of the mirror at any adjusted position, and the several swiveled and pivoted connections serve to allow the 45 mirror 25 to be positioned at any desired

point or angle in front of the larger mirror 4, to enable the user to see the back of the head or the side thereof, in a well known manner.

From the foregoing it will be seen that a 50 useful and ornamental device has been provided for installation on the walls or bathrooms or other rooms for containing medicines, toilet articles, or for general uses; that the same may be readily moved from one location to another without requiring the services of an expert electrician to connect up the wiring; that the cabinet is rendered stronger and more durable by the reinforcement of the metal, tubular protectors which help to connect the wings to the back of the cabinet; and that the provision of the universally adjustable supplemental mirror serves to fulfill a much desired want for such a convenience. 60 65

What is claimed is:—

1. A portable bathroom cabinet comprising a cabinet box having a mirror door at the front; side wings secured to the box against the rear wall to provide a space for 70 electric cable in the rear of the box; and electric lamps carried by said wings arranged behind the plane of the mirror to project light in front of the mirror without being reflected therefrom. 75

2. A portable wall cabinet for bathrooms comprising a cabinet box having a mirror door; side wing boards secured against the rear wall of the box having a space for 80 electric cables; electric lamps on the face of the wing boards and arranged behind the plane of the mirror; and electric wiring behind the wing boards for said lamps; said wing boards each having a channel to receive the electric wiring. 85

In testimony, that I claim the foregoing as my own, I have hereto affixed my signature.

ROBERT P. KING.
